ABSTRACT: A lamp shade is provided which consists of a spiral strip cut out of a plane sheet and is maintained in a hybrid spiral and helical path by means of strips or filaments extending transversely of the turns of the spiral strip and attached thereto in the points of intersection. To provide such a lamp shade a method is provided, according to which a spiral strip is first cut out of a plane sheet and is then pulled out perpendicularly to its plane by attaching supporting strips or filaments to the spiral strip in predetermined attachment areas thereof.

LAMP SHADE AND METHOD OF MANUFACTURING SAME

BACKGROUND OF THE INVENTION

This invention relates to a lamp shade comprising at least one spiral strip cut out of a plane elastic sheet and pulled out perpendicularly to the plane of said sheet so as to run in a path forming a combined or hybrid spiral and helix.

The turns of the spiral strip have the same function as the shade rings of a known type of lamp shade comprising a plurality of such rings arranged one above the other, viz., to cut off the direct light emitted by a light source arranged within the lamp shade, either completely or in part, and to reflect light in a more or less diffuse manner so as to provide a suitable combination of direct and indirect light.

The spiral construction has the advantage over lamp shades composed of rings that the spiral can be cut out of a sheet with less waste of material and, from a manufacturing point of view, it is also an advantage that the shade elements formed by the spiral turns are in one piece, or a few pieces in case more than one spiral is used, rather than forming a considerable number of separate elements of different dimensions. However, the systems so far known for maintaining the turns of the spiral strip in the desired geometrical shape have not been entirely satisfactory. Thus, it has been proposed to secure one edge of the spiral strip to a rigid self-carrying bar bent into the shape of a spiral, but this construction will not allow for more than a few turns of small diameter, if the cross-sectional dimensions of the bar are to be kept within reasonable limits. It has also been proposed to maintain the turns of the spiral strip in position by means of a rigid frame placed inside the shade. This construction, however, is heavy and it is difficult to bend the spiral strip in a regular manner. Besides, the frame, which can be seen between the spiral turns, is alien to the idea of the spiral lamp shade.

SUMMARY OF THE INVENTION

According to the invention, the spiral strip is arranged and maintained in the desired geometrical shape by means of a plurality of elongated flexible supporting elements extending transversely of the turns of said strip and being distributed along the circumference thereof, said supporting elements being attached to said turns at each point of intersection therebetween.

In this arrangement, the shape of the spiral shade is not sustained by a rigid supporting frame, but by the cooperation of two components, viz., spiral strip and supporting elements, which are both flexible. In fact, the supporting elements are distended by the spiral turns into the desired shade profile, while on the other hand the spiral strip is bent in turns of the desired contour by the distended supporting elements.

The lamp shade according to the invention may be made alternatively in a hanging or a standing design. In the former case, the supporting elements need not be capable of withstanding compressional forces in their longitudinal directions and therefore may e.g., consist of strings or filaments. In the standing design, however, where the lamp shade is supported from below, the supporting elements must be in the form of elastic ribs, e.g., slender strips cut out of a sheet material. The latter form of supporting elements may also with advantage be used for lamp shades of hanging design.

In both designs it is necessary, in order to obtain a regular and uniform course of the turns, that the points of attachment are correctly placed on both the spiral strip and the supporting elements and that the relation between the weight and the elasticity of the supporting elements is suitably balanced, since this balance of forces is the very factor that determines and maintains the shape of the lamp shade.

Owing to the fact that the lamp shade is maintained in the desired shape by the cooperation of elastic forces as described, the lamp shade is to a high degree resistant to mechanical injury.

The invention also relates to a method of making a lamp shade of the kind described. According to the invention, this method comprises the steps of cutting a spiral strip out of a plane sheet, forming distinct attachment areas in spaced points along the length of said strip, providing a system of elongated elastic supporting elements, pulling out said spiral strip perpendicularly to its plane and attaching said supporting elements to said strip in the attachment areas thereof in cyclical succession.

10

BRIEF DESCRIPTION OF THE DRAWING

FIG. 1 shows a spiral strip cut out of a plane elastic sheet for use in a lamp shade according to one embodiment of the invention.

FIG. 2 shows a set of supporting elements also cut out of a plane sheet or foil for supporting the spiral strip of FIG. 1 in a hybrid spiral and helical path.

FIG. 3 shows in side elevation a lamp shade made from a 20 spiral strip of the type illustrated in FIG. 1 and a set of supporting elements of the type illustrated in FIG. 2.

FIG. 4 shows in side elevation a lamp shade according to another embodiment of the invention.

FIG. 5 is a cross section through a lamp shade of standing 25 design according to a further embodiment of the invention.

FIG. 6 shows on a larger scale a plan view of a fraction of a supporting element.

FIG. 7 is a plan view of a fraction of a spiral strip.

DESCRIPTION OF THE PREFERRED EMBODIMENTS

All the lamp shades shown in the drawing are composed of two components, viz., a spiral strip as illustrated in FIG. 1 and a set supporting elements as illustrated in FIG. 2. The spiral strip 35 1 is provided along one edge thereof with slits 5, each opened up to the edge by a cut 6. Each supporting element is provided with incisions 4 from one edge thereof. Both the spiral strip illustrated in FIG. 1 and the system of supporting elements illustrated in FIG. 2 are cut out of plane sheets, e.g., of artificial 40 resin.

To make a lamp shade as that illustrated in FIG. 3, the spiral strip 1 of FIG. 1 is pulled out perpendicularly to its plane and the supporting elements 3 of FIG. 2 are introduced through the cuts 6 into the slits 5 of the spiral strip in cyclical succession in such a manner that the incisions 4 are engaged with the slits 5. Thereby the spiral strip automatically assumes the desired hybrid spiral and helical shape and the spiral strip is at the same time caused to slant in its transverse direction at an angle that may vary along the length of the spiral strip. The top portion of the lamp shade is formed by bending the material at the center of the spiral of FIG. 1 into the form of a cone. At the bottom of the lamp shade, the free end of the spiral strip may be attached to the same point of a supporting element as the penultimate turn of the spiral strip so as to provide a smooth runoff.

The geometrical shape of the lamp shade will be determined by the positions of the slits 5 and the incisions 4, and it may easily be determined in advance how these positions should be selected in order to obtain a certain desired geometrical shape of the lamp shade.

In the embodiment illustrated, as is apparent from FIG. 1, the slits are located, as referred to the plane state of the strip 1, in different angular positions from turn to turn with respect to the axis of the spiral. In this manner, the spiral is automatically subjected to a certain twist, which is suitable to stabilize the shape of the shade. If desired, it is also possible, however, to arrange the slits of the various turns in the same angular positions in all the turns, only in that case the lamp shade can not be contracted towards its lower end, if one spiral strip only is used.

The precise manner of attachment between the spiral strip 1 and the supporting elements 3 is not essential, but it is important that the spiral strip should in any case have distinct attachment areas, in which to attach the supporting elements. It

75

is also desirable though less important that the points of attachment of the supporting elements should be defined in advance.

It is not essential that the supporting elements are formed in a lattice pattern as illustrated in FIG. 2, though this form of supporting elements is advantageous from a practical point of view, because it becomes easy to keep the supporting elements in the correct order for cyclical engagement with the slits of the spiral strip. It will be understood that when this form of supporting element is used, the connecting end pieces are cut away when the mounting operation has been completed.

The lamp shade of FIG. 4 is composed of three spiral strips, which are mutually connected and arranged in continuation of one another, the central portion of each of the spiral strips being cut away. In this manner it is possible to obtain a lamp shade, in which the spiral turns have opposite slants at the top and the bottom of the shade with the composite spiral strip extending continuously and smoothly from one end of the lamp shade to the other.

In the embodiment illustrated in FIG. 6, the supporting elements have increased width adjacent the incisions 4 in order to avoid weakening of the supporting elements in these areas.

I claim:

1. A lamp shade comprising at least one spiral strip cut out

of a plane elastic sheet and running in a path forming a hybrid spiral and helix, and a plurality of elongated flexible supporting elements extending transversely of the turns of said strip and being distributed along the circumference thereof, said supporting elements being attached to said turns at each point of intersection therebetween.

5 2. A lamp shade as in claim 1, in which the points of said strip, at which said supporting elements are attached, are located as referred to the plane state of the strip, in different angular positions from turn to turn with respect to the axis of the spiral.

10 3. A lamp shade as in claim 1, in which said supporting elements are flat and are provided with incisions from at least one edge, the strip being provided along one edge with slits each opened to the edge by a cut, the incision sections of said supporting elements being engaged in said slits of said strip.

15 4. A method of making a lamp shade comprising the steps of cutting a spiral strip out of a plane sheet, forming distinct attachment areas in spaced points along the length of said strip, providing a system of elongated elastic supporting elements, pulling out said spiral strip perpendicularly to its plane, and attaching said supporting elements to said strip in the attachment areas thereof in cyclical succession.
